ATTORNEY

UNITED STATES PATENT OFFICE

WILLIAM D. SCALF, OF PINEVILLE, KENTUCKY

DROP-SEAT GARMENT

Application filed August 19, 1931. Serial No. 558,113.

My invention relates to under and outer garments, and it consists in the constructions, arrangements, and combinations herein described and claimed, and is an improvement 5 of the garment disclosed in my pending application Serial No. 478,707, filed Aug. 29, 1930.

It is an object of my invention to provide a novel form of drop-seat which will be automatically adjusted vertically and circumferentially about the body of a wearer, and thereby affording the greatest possible comfort.

It is a still further object of the invention 15 to provide a garment embodying a drop-seat which may be readily lowered, when required, and automatically adjusted about the person when assuming an erect position, all of which features are made possible without the need for fastening means, such as buttons or the like.

Additional objects, advantages and features of invention will be apparent from the 25 following description, considered in conjunction with the accompanying drawings, wherein:

Figure 1 is a perspective view of a garment constructed in accordance with my invention,

30 Figure 2 is a rear view of the garment, Figure 3 is a perspective view of a modified form of the garment, and

Figure 4 is a rear view thereof.

The garment in the present instance, comprises a front body portion 10 having leg members 11, and a back body portion 12. The back portions of the leg members 11 are secured to the front portion of the garment, as at 13. The rear portions of the leg members 11, at the point of attachment 40 with the seam 13, stop short of the waist-line of the garment, as at 15, forming a drop seat 16.

As clearly shown in Figs. 1 and 2, the 45 drop seat 16 is free of direct attachment to the garment proper, at its upper edge. The seat 16 is of substantially the same width as the garment at the waist-line, and along the upper edge thereof I secure by stitching 50 or otherwise, an elastic strap 17.

The strap 17 is of a length less than the width of the drop-seat 16 and therefore will gather the material of the drop-seat, as indicated at 18, providing the necessary fullness in the seat so as to readily conform to 55 the contour of the body of the wearer.

The back portion 12 of the garment extends well below the point of attachment, of the leg members 11, terminating in a flap 19, which lies beneath the drop-seat 16.

Upon each upper corner of the drop-seat 16, I provide an elastic-strap 20, one end thereof being suitably secured by stitching, while the opposite end of the strap is secured by stitching to the lower edge of respective arm holes 21. It will be understood that the straps 17 and 20 may comprise a single strip, if desired.

It should be noted that the straps 20 extend between the drop-seat and arm holes so as to lie at a slight angle to a vertical medial line, and by reason of this arrangement, the drop seat 16 will be caused to readily assume the contour of the wearer. Also, by reason of this construction, the straps 20 do not exert 75 a direct downward pull upon the shoulder straps, but tend to evenly divert the tension of the straps 20 to the front, top and rear portions of the shoulder straps.

In the use of this garment it is only necessary to exert a lateral pull upon the seat 16 so as to stretch the elastic straps 17 to the full width of the garment and then lowering the seat 16 by tensioning the elastic straps 20. The flap 19 may be adjusted as desired. 85 When the wearer assumes an erect position, the flap 19 is adjusted and the elastic straps 20 will return the drop-seat 16 to its normal raised position. The strap 17 will draw the seat 16 laterally into conformity with the 90 body of the wearer, as will be readily understood.

In Figures 3 and 4 a modification of the garment is shown and corresponding elements of the garment are designated by reference characters as applied to Figs. 1 and 2.

In the modified form of the device, elastic straps 23 are secured to respective corners 24 of the drop-seat, these straps extending circumferentially of the garment and are se- 100

cured to the front part of the garment as at 25. The straps 23 may, of course, be continuous of the strap 17, if desired, but in such event the strap adjacent the top edge of the drop seat must be suitably stitched in order to provide the gathered effect to the seat.

The use of this form of garment is identical with the first form described. The straps 23 it will be understood draw the seat circumferentially, to a slight extent.

While I have shown and described my drop-seat as applied to a particular form of garment, it will be understood that the device may be readily applied to overalls, children's play garments, and numerous other garments, and I therefore do not limit myself to the particular adaptation herein shown and described.

I claim:

- 20 1. A garment comprising a body portion having arm holes, leg members upon said garment, a drop-seat formed with said body portion, an elastic strap member secured to the upper edge of said seat, and elastic strap members secured to and extended between the lower edge of said arm holes and upper portion of said drop seat.
- 25 2. A garment comprising a body portion having arm holes, leg members upon said garment, a drop-seat formed with said body portion, an elastic strap member secured to the upper edge of said seat, said strap being of a length less than the width of the drop seat, and elastic strap members secured to and extended between the lower edge of said arm holes and upper portion of said drop seat.
- 30 3. A garment comprising a body portion having arm holes, body portion upon said garment, a drop-seat formed with said leg members, an elastic strap member secured to the upper edge of said seat, said strap being of a length less than the width of the drop seat, an elastic strap member secured to the upper edge of said drop seat and to a front portion of said garment, and elastic strap members secured to and extended between the lower edge of said arm holes and upper portions of said drop seat.

50 WILLIAM D. SCALF.
